ANCHOR WINCH

Edgar B. Thomas and Charles W. Heineman,
Connersville, Ind., assignors to Thomas and
Heineman, Inc., Connersville, Ind., a corpora-
tion of Indiana

Application June 4, 1947, Serial No. 752,450

5 Claims. (Cl. 254—187)

1

This invention relates to an improved anchor winch designed for small boats.

An object of this invention is to provide an improved winch which will automatically lock when released by the user so that the anchor cable or rope will not reel out.

Another object of this invention is to provide a winch of this kind which upon movement of the locking means to released position will frictionally resist unwinding of the reel so that when the anchor strikes bottom the reel will immediately stop unwinding and thereby prevent kinking or snagging of the line.

A further object of this invention is to provide a winch of this kind which is of simple construction so that it will not readily get out of order.

A further object of this invention is to provide a winch of this kind wherein the operator may regulate the braking pressure on the reel as the latter unwinds.

With the above and other objects in view, my invention consists in the arrangement, combination and details of construction disclosed in the drawings and specification, and then more particularly pointed out in the appended claims.

In the drawings,

Figure 1 is a detail side elevation, partly in vertical section, of an anchor winch constructed according to an embodiment of our invention.

Figure 2 is a sectional view taken substantially on the line 2—2 of Figure 1.

Figure 3 is a fragmentary sectional view taken substantially on the line 3—3 of Figure 1.

Figure 4 is a sectional view taken on the line 4—4 of Figure 1.

Referring to the drawing, the numeral 10 designates generally a frame member of substantially U-shape which is formed with vertically disposed legs 11 and 12, and a horizontal bight 13. The leg 11 is formed with a right angularly outwardly extending member 14 terminating in an upstanding bearing 15. The leg 12 is substantially shorter in length than the leg 11 and is formed with a right angularly outwardly extending extension 16 with which an upright bearing member 17 is formed.

A crankshaft generally designated as 18 has the shaft member 19 thereof journaled through the bearing members 15 and 17 and includes an L-shaped crank member 20 having a handle 21 secured on the lower horizontal side 22 thereof. An angle shaped clamping bar generally designated as 23 is fixed to the frame 10 at an angle formed by the leg 12, and the right angle extension 16. The angle bar 23 extends from opposite

2

sides of the frame 10, as shown in Figure 1, and the vertical side 24 thereof constitutes a fixed clamping jaw which is adapted to engage at one side of a support 25, as shown in Figure 4.

The upper side 26 of the clamping bar 23 is horizontal and has fixed thereto an arched housing 27 on its inner end is formed with an L-shaped right angular flange 28 to the inner side of which is secured by fastening members 29, a U-shaped fixed brake band 30. A reel or winding drum 31 is loosely mounted on the shaft 19 and has one side thereof confronting the brake band 30 so that the reel 31 will be braked against rotation in an unwinding direction, as will be hereinafter described.

A spring 32 is disposed about the shaft 19, bearing at one end against a thrust washer 33 which engages one side of the reel 31. The spring 32 engages in a cup-shaped housing 34 formed with an annular flange 35, and the latter is keyed or pinned to the shaft 19 by means of a locking pin 36 formed with an inwardly projecting upper end 37 engaging through the flange 35, as shown in Figure 2.

The side of the reel or drum 31 opposite from the spring 32 is formed with a pair of clutch forming sockets or openings 38 within which a pair of clutch pins 39 are adapted to normally engage. The clutch pins 39 are carried by a plate 40 formed with a hub 41 secured by means of a pin or other securing means 42 to the shaft 19.

A toothed ratchet 43 is in the present instance formed integral with the hub or bushing 41 and engages within the housing 27. A U-shaped member 44 is fixed to the upper side of the extension 16 and has the upright legs thereof engaging on opposite sides of the ratchet wheel 43. The ratchet wheel 43 is loosely disposed between the legs of the U-shaped member 44 so that the ratchet wheel may have endwise movement with the shaft 19 when the latter is moved to declutching position.

A spring-pressed pawl 45 is rockably mounted on a shaft or pin 46 engaging through the legs of the U-shaped member 44 and is constantly urged to ratchet engaging position by means of a spring 47. The horizontal upper side 26 of the angle clamping member 23 is formed with a pair of barrels 48 within which one side 49 of an L-shaped adjustable clamping member 50 is adapted to loosely engage. The other side 51 of the clamping member 50 extends downwardly in parallel relation to the vertical side 24 of the angle member 23 and has secured thereto a clamping

jaw 52 confronting the vertical side or jaw 24 of the angle member 23.

The horizontal side 49 of the clamping member 50 is formed with threads 53 on which a wing nut 54 is threaded. In this manner the adjustable jaw 52 may be pressed against the supporting member 25 on the side of the latter opposite from engagement of the stationary or fixed jaw 24 therewith.

A cable or rope 55 is fixed at one end to the reel or drum 31 and is wound about the reel or drum 31. A U-shaped cable guide 56 is fixed to the bight 13 of the frame 10 with the cable or rope 55 engaging between the parallel legs of the rope guide 56 as shown in Figure 2.

In the use and operation of this winch, the cable or rope 55 is wound about the reel 31, being extended through the guide 56. When it is desired to drop the anchor, shaft 19 is moved endwise or to the right, as viewed in Figure 2. This endwise movement of the shaft 19 will move clutching pins 39 to released position so that the reel or drum 31 may freely rotate in an unwinding direction. However, at the time the clutch pins 39 are in declutching position relative to the pin openings or sockets 38 formed in the reel or drum 31, spring 32 is placed under additional tension by compressing of this spring so that the reel or drum 31 will be spring tensioned against the brake band 30. This band being stationary, the reel or drum 31 will be frictionally held against free rotation, the brake band providing sufficient drag on the reel or drum 31 so that as soon as the anchor or weight strikes bottom, the reel or drum 31 will stop rotating. In this manner the cable or rope 55 will not be paid out unduly after the anchor strikes bottom. As soon as the anchor strikes bottom, shaft 19 may be released so that spring 32 will move clutching pins 39 inwardly toward the reel 31 and into the clutch sockets or openings 38. Inasmuch as the ratchet 43 is held against rotation in an unwinding direction by the spring-pressed pawl 45, as soon as the clutching pins 39 engage in the openings 38 the reel 31 will be locked against further unwinding.

The housing 34 is of such length that the inner end thereof may be disposed in contacting relation with respect to the washer 33 after the clutch is released so that any desired manual pressure may be placed on reel 31 to hold the latter in braking position with respect to the stationary brake band 30. The frictional contact between housing 34, and washer 33 with the hub of reel 31 will also provide an additional braking means which will positively hold reel 31 against rotation. At the time the clutch pins are in clutching position, spring 32 is substantially relaxed so that reel 31 may be freely rotated by the crank-shaft 18 in a winding direction.

We do not mean to confine ourselves to the exact details of construction herein disclosed, but claim all variations falling within the purview of the appended claims.

What we claim is:

1. An anchor winch comprising a frame, a crankshaft rotatably carried by said frame, a reel rotatable on said shaft, correlated clutch means carried partly by said reel and partly by said crankshaft, a spring about said shaft bearing at one end against said reel for urging the latter to clutching position, means anchoring the opposite end of said spring to said crankshaft, a stationary brake means confronting the side of said reel opposite from said spring whereby upon endwise

movement of said crankshaft to declutching position said reel will be spring urged endwise against said braking means, and pawl and ratchet means holding said crankshaft against turning in a reel unwinding direction.

5. An anchor winch comprising a substantially U-shaped frame, an angle shaped clamping bar fixed to one leg of said frame, a crankshaft journaled through both legs of said frame, a reel 10 journaled on said shaft between the legs of said frame, correlated clutch means carried partly by said reel and partly by said shaft, a spring about said shaft bearing at one end against said reel, means securing the opposite end of said spring 15 relative to said shaft, a brake band, means fixedly supporting said band relative to said frame in a position confronting the side of said reel opposite from said spring, endwise movement of said shaft to declutching position tensioning said spring 20 against said reel whereby the latter will be spring-pressed against said brake means, and pawl and ratchet means holding said crankshaft against rotation in a reel unwinding direction.

3. An anchor winch comprising a substantially U-shaped frame, an angle shaped clamping bar fixed to one leg of said frame, a pair of tubular barrels carried by said bar, a pair of L-shaped clamping members having one side thereof loosely engaging in said barrels and the other side there- 30 parallel with a side of said bar, a jaw carried by said other side of each of said clamping members confronting the other side of said bar, a crankshaft journaled through both legs of said frame, a reel journaled on said shaft between the 35 legs of said frame, correlated clutch means carried partly by said reel and partly by said shaft, a spring about said shaft bearing at one end against said reel, means securing the opposite end of said spring relative to said shaft, a brake band, means fixedly supporting said band relative to said frame in a position confronting the side of said reel opposite from said spring, endwise movement of said shaft to declutching position tensioning said spring against said reel whereby the latter will be spring-pressed against said 40 band, means fixedly supporting said band relative to said frame in a position confronting the side of said reel opposite from said spring, endwise movement of said shaft to declutching position tensioning said spring against said reel whereby the latter will be spring-pressed against said 45 brake means, and pawl and ratchet means holding said crankshaft against rotation in a reel unwinding direction.

4. An anchor winch comprising a frame, a 50 crankshaft rotatably carried by said frame, correlated clutch means carried by said shaft and reel, pawl and ratchet means holding said shaft against rotation in an unwinding direction, stationary brake means confronting one side of said reel and fixed relative to said frame, a spring about said shaft, and an abutment carried by said shaft against which one end of said spring engages, the opposite end of said spring engaging against said reel, said spring normally urging said 55 reel and shaft in opposite directions to thereby hold said clutch means in clutching position, endwise movement of said shaft in a declutching direction increasing the tension of said spring against said reel whereby the latter will frictionally contact said brake means.

5. An anchor winch comprising a frame, a 60 crankshaft rotatably carried by said frame, correlated clutch means carried by said shaft and reel, pawl and ratchet means holding said shaft against rotation in an unwinding direction, stationary brake means confronting one side of said reel and fixed relative to said frame, a spring about said shaft, an abutment carried by said shaft against which one end of said spring engages, the opposite end of said spring engaging 65 70 75

against said reel, said spring normally urging said reel and shaft in opposite directions to thereby hold said clutch means in clutching position, end-wise movement of said shaft in a declutching direction increasing the tension of said spring against said reel whereby the latter will frictionally contact said brake means, and a cup-shaped member carried by said shaft about at least a portion of said spring and adapted to engage said reel when said spring is under maximum compression to thereby provide increased braking force against said reel, and increased pressure of said reel against said brake means.
